28 Claims. (Cl. 62—106)

1

This invention relates to the art of congealing and apparatus for use in connection therewith.

One of the objects of this invention is to provide an improved method of obtaining heat transferring relationship between relatively moving parts. Another object is to provide improved congealing apparatus which is practical and efficient in operation. Other objects will be in part obvious and in part pointed out hereinafter.

The invention, accordingly, consists in the features of construction, combinations of elements, arrangements of parts and in the several steps and relation and order of the same, all as will be herein illustratively described, and the scope of the application of which will be indicated in the following claims.

In the accompanying drawings in which is shown an embodiment of this invention,

Figure 1 is a side elevation of an assembled machine embodying the invention showing the side of the cover removed;

Figure 2 is a longitudinal horizontal staggered section taken on the line 2—2 of Figure 1 which line 2—2 has a bend as indicated at A;

Figure 3 is a vertical section taken on the line 3—3 of Figure 1;

Figure 4 is a detailed plan view of the evaporator of Figure 1 having parts broken away to show how the various evaporator sections are interconnected;

Figure 5 is a longitudinal vertical section through an evaporator tube taken on line 5—5 of Figure 4;

Figure 6 is an enlarged longitudinal horizontal section taken on the line 6—6 of Figure 1;

Figure 7 is a vertical section on an enlarged scale taken on line 7—7 of Figure 1 showing apparatus for applying a liquid film to the under side of a traveling flexible belt and apparatus for supplying a liquid to the upper side of the same belt;

Figure 8 is a diagrammatic showing of a system for circulating the liquid applied by the apparatus shown in Figure 7; and

Figure 9 is a perspective view on an enlarged scale of the trough of the apparatus for supplying liquid to the upper side of the belt shown in Figure 7.

In the present embodiment, an endless thin flexible metal belt is caused to travel over two spaced pulleys and to slide over the convex curved surface of a stationary evaporator which cools the belt as it passes over the evaporator. The evaporator is refrigerated by the usual ammonia or other expansion system. Liquid or solid foodstuffs to be frozen are supplied to the outer surface of the belt as it passes over the evaporator

2

surface, and the congealed product peels from the belt as the belt passes over one of the pulleys.

The heat transferring relationship between the belt and the evaporator surface is improved by the application of a film of non-congealing liquid to the under side of the belt. This film of liquid serves also to lubricate the contact between the belt and the evaporator surface to minimize sliding friction therebetween and serves further as a means for maintaining the belt and the evaporator surface in close contact by means of atmospheric pressure.

Referring now to Figures 1, 4, and 5, the evaporator, generally indicated at 10, comprises a series of curved tubes 120 (Figures 4 and 5) rectangular shaped in cross section (Figure 3) which are welded together along their longitudinal side walls. The ends of these tubes are closed by end plates 121 and 122 (Figures 4 and 5). As best shown in Figure 4, the ends of abutting side walls of the rectangular-shaped tubes stop short of and so are spaced from end plates 121 and 122. Thus, two passageways 124 and 125 are provided extending across the ends of the evaporator. Inlet and exhaust pipes 126 and 127 respectively are connected to the side of the evaporator (Figures 1 and 4) and connect with the ends of passageways 124 and 125. With this construction, a suitable refrigerant in liquid form may be supplied to the evaporator through pipe 126. The refrigerant flows across the connected ends of the tubes 120 and up through the tubes. The spent refrigerant in the form of vapor and any unevaporated liquid is collected at the upper ends of the tubes and returned to the compressing system (not shown) through pipe 127. As shown in Figures 4 and 5, this construction provides an outer convexly curved, continuous smooth refrigerated surface which is preferably highly polished or provided with a plating which gives it a smooth surface.

The framework supporting this evaporator has four legs 30, 31, 32, and 33 (Figures 1 and 2) which are braced in their lower portions by a pair of transverse braces 34 and 35 and a pair of longitudinal braces, one of which is shown at 36 (Figure 1). The connections between these braces and the legs may be made in any suitable manner, such as by welding. The upper ends of the legs are secured by bolts to a pair of bent longitudinal channel bars, generally indicated at 37 and 38, at either side of the evaporator and which extend throughout the length of the machine. The bent channel bars may be conveniently constructed by joining two straight sections 39 and 40 at an angle by means of a joining plate 41. Extending transversely between the channel bars are a pair

of braces 45 and 46 which are secured to the side walls of the channel bars in any suitable manner, such as by a right-angle flange and bolts shown on the left-hand end brace 45 in Figure 2. The evaporator 10 is rigidly secured to and supported by the side channel bars 37 and 38 by means of uprights 96, 97, 98, and 99 (Figure 2) secured to the channel bars and secured at their upper ends to cross bars 94 and 95 extending beneath and welded to the underside of the evaporator tubes 120.

These channel bars carry a pair of cylindrical pulleys, generally indicated at 47 and 48, mounted at opposite ends of the machine and around which the flexible belt is passed. Pulley 48 is mounted on a stationary shaft 49 (Figure 1) and comprises a hub 50 (Figure 6) which is rotatably mounted with respect to shaft 49 in bearings 51 and 52 and held in proper axial position thereon by a pair of collars 57 and 58 which are secured to shaft 49 by set screws 80 and 59. Two sets of spokes 53 and 54 radiate outwardly from the hub and are secured to the inside wall of a metal cylinder 75 in any suitable manner, such as by welding. The external surface of this cylinder, which is the running surface of the pulley, is preferably covered with a sheet of rubber 55 which prevents transverse deflection in the endless flexible belt 56 as it passes over the pulley.

The outer ends of shaft 49 are supported by a carriage, generally indicated at 60, slidably mounted on the horizontal sections 40 of the channel bars. This carriage comprises a transverse bar 61 which has a pair of cylindrical horizontal rods 62 and 63 secured at right angles to its ends. These rods are positioned above channel bars 37 and 38 respectively and each rod is mounted for longitudinal movement lengthwise of the machine in a pair of journals which are secured to the tops of the channel bars. Thus, rod 62 is slidably mounted in journals 64 and 65 and rod 63 is slidably mounted in journals 66 and 67. The outer ends of rods 62 and 63 carry blocks 68 and 69 which are secured to sliding plates 71 and which support shaft 49. The carriage, which thus slidably supports pulley 48, is resiliently urged to the right, as shown in Figure 1, by means of a compression spring 78.

Referring to Figures 1 and 6, an angle bar, generally indicated at 73, is secured to the inner ends of sections 40 of channel bars 37 and 38. This angle bar has one side secured to the channel bars and its other side 74 extends upwardly at right angles thereto. The opposed faces of transverse bar 61 and side 74 each have annular rings 76 and 77 thereon (Figure 6) which serve to align the ends of spring 78. To draw the carriage back against the compression of spring 78, as when it is desired to place a new belt on the machine, a rod 79 is provided. This rod extends through the center of spring 78 and has a nut 81 formed on its left-hand end to the left of side 74 (Figure 6). It passes through this side through a hole of slightly greater diameter than the diameter of rod 79 and threads into transverse bar 61. Thus, by turning the rod in one direction by nut 81, the rod threads a greater distance into transverse bar 61 moving the carriage 60 and pulley 48 to the left, as viewed in Figures 1 and 6. When the nut is turned in the opposite direction, the carriage is resiliently urged to the right by spring 78.

Pulley 47 (Figure 1) is of substantially the same construction as pulley 48 and is secured to a shaft 82 which is parallel to the shaft of pulley

48. The ends of this shaft are journaled in a pair of blocks 83 and 84 (Figure 2) which are rigidly secured to the left-hand ends of channel bars 37 and 38 respectively. A pulley 85 is secured to one end of shaft 82 and this pulley is connected by a belt 86 to a motor 87. This motor preferably drives belt 86 through a transmission 150 which permits the rate of drive of the belt 56 to be varied. The cylinder of pulley 47 is covered with a sheet of rubber which not only prevents transverse deflection of the belt but also insures driving traction between this pulley and the belt.

The endless belt 56 (Figure 1) which rides on pulleys 47 and 48 and travels across the evaporator is preferably made of thin metal, such as described in my Patent No. 2,078,938, and has a pair of V-shaped rubber tracks 88 and 89 (Figures 6 and 7) secured to its edges. These tracks engage V-shaped grooves formed in the peripheries of annular rings secured to the opposite ends of each pulley. For example, pulley 48 has annular rings 90 and 91 secured to its ends and these rings carry V-shaped grooves 92 and 93 respectively. These grooves not only provide the necessary traction to drive the belt through the medium of pulley 47 but also serve to keep the belt in accurate alignment with the evaporator.

This belt 56 (Figure 1) thus passed around the pulleys 47 and 48 is maintained under tension and against the evaporator 10 by means of the compression spring 78 pushing outwardly on the carriage 60, which influence is imparted to the pulley 48. As above pointed out, the belt is caused to slide along the evaporator and to travel about the pulleys by the friction drive between the belt and the driving pulley 47. The angle with which the belt approaches the leading edge of the evaporator 10 from the top of the roller 48 is maintained equal to the tangent of the curve of the evaporator surface at its leading edge, so that no bending of the belt takes place along this line and so that the belt starts its contact with the evaporator surface at this line. This is accomplished by making the carriage rods 62 and 63 parallel to said tangent and by making the radius of the pulley 48 equal to the perpendicular distance between the axis of the rods 62 and 63 and the leading edge 101. Thus, as the roller 48 adjusts itself lengthwise of the apparatus, the plane of tangency between the belt and the pulley is maintained coincident with the plane of tangency of said leading edge of the top surface of the evaporator. In this way, the tension on the belt is maintained constantly while the belt at all times is in contact with the leading edge 101.

The non-adjustable pulley 47 is also so positioned with respect to the following edge 100 of the evaporator surface that the plane of tangency between the belt and the pulley 47 is coincident with the plane of tangency of the evaporator surface along the following edge 101. Thus, in operation, the flexible endless belt is at all times held in contact with the entire refrigerated surface of the evaporator 10 without permitting any bending of the belt to take place as it approaches the evaporator or as it leaves it.

Liquid, preferably propylene glycol, is supplied to the header 102 (Figures 1 and 8) under a substantially constant head by means of a pipe 111 connected with the bottom of a reservoir 109. As the belt moves past the outlets 103 (Figure 7) of the header, the under surface of the belt is wetted by the propylene glycol, and as the belt continues to move over the evaporator sur-

face, the propylene glycol spreads sideways to form a continuous film. This film provides a continuous heat transferring medium between the evaporator and the belt, which medium has a high coefficient of heat transfer as compared with a gaseous medium. Propylene glycol or a similar liquid is preferred since it is non-corrosive and has the capacity of absorbing water to the desired extent. Thus, any water that might condense on the belt is absorbed by the propylene glycol and does not form a separate liquid film in the propylene glycol. Further, propylene glycol solution does not congeal at the operating temperatures employed, has a relatively low viscosity at these operating temperatures, and serves as a lubricant between the belt and the evaporator surface. Further, it does not attack the rubber tracks of the belt nor the rubber surfaces of the cylinders and the pulleys.

The liquid forming the film is taken from the belt after it passes from the evaporator surface and before it reaches the pulley 47 by means of a wiper 105 (Figure 8) extending across the belt. The liquid removed by the wiper runs down into a trough 106 and is removed therefrom by means of a line 107 connected with a small pump 108 which discharges through the line 110 into the reservoir 109.

As has been pointed out hereinabove, this machine is suitable for freezing both liquids and solids. When it is used for freezing a liquid, the apparatus shown in Figures 1, 7, and 9 may be used for spreading the liquid on the belt. The apparatus comprises a trough 115 (Figure 9) which has grooves 116 and 117 in its ends by means of which it is slidably mounted on a pair of vertical guide rails 130 and 131 (Figures 1 and 7) which are secured to evaporator 10 in any suitable manner, such as by supports 132 and 133. When the machine is in operation, the trough rests by gravity on the surface of belt 56 and is free to adjust itself to variations in the belt surface. Liquid is fed to trough 115 through a supply pipe 134, and the rate of flow into the trough 115 is governed by a valve 119 operated by a handle 119a. Referring to Figure 1 in which the belt moves to the left, the right-hand side of trough 115 is lower than the left, and thus, the liquid to be frozen overflows down this side of the trough and is spread evenly over the side of the trough before it reaches the surface of the belt passing thereunder. In order to supply liquid only to that portion of the belt which passes over the evaporator, the ends of trough 115 are tapered upwardly (Figure 7). Thus, by this apparatus, liquid is applied evenly and efficiently to the belt.

To exclude moisture from the interior of the flexible belt and in so far as possible from condensing and freezing on the under side of evaporator 10 and from condensing on other cooled parts of the apparatus, the apparatus is preferably enclosed by a suitable cover 112 provided with heat insulating qualities, which extends down to a storage bin generally indicated at 201. Furthermore, the apparatus within cover 112 is refrigerated by means of an expansion coil 113, shown in Figures 1 and 2, which coil also serves to condense any moisture entering the closure 70 and so provides an additional protection against condensation of moisture on the interior of the belt.

The apparatus, as shown, is constructed to provide the freezing surface of the belt 56 only

slightly tipped from the horizontal. This construction has the advantage of aiding in the application of liquid and solid foodstuffs to the flexible belt in such manner that no excess application of the material to be frozen is necessary. This is advantageous particularly when materials such as cream and eggs are frozen, where the temperatures necessary for congealing must be quickly reached in order to avoid destructive effects.

As has been pointed out hereinabove, the belt rotates in a counter-clockwise direction as viewed in Figure 1. Thus, the articles or liquid to be frozen are placed upon the belt to the right of the evaporator and the belt is moved at the correct speed to freeze the article or liquid by the time it leaves the evaporator. These articles or the liquid are removed from the belt at the left-hand end of the machine by the flexing of the belt as it passes over pulley 47, and the frozen material thus removed passes down a chute 200 into bin 201 through opening 202.

Thus, it will be seen that I have provided an efficient and practical method and apparatus in which the several objects hereinabove mentioned, as well as many others, are successfully achieved.

As many possible embodiments may be made of the mechanical features of the above invention and as the art herein described might be varied in various parts, all without departing from the scope of the invention, it is to be understood that all matter hereinabove set forth, or shown in the accompanying drawings, is to be interpreted as illustrative and not in a limiting sense.

I claim:

1. In congealing apparatus of the class described, in combination, a stationary refrigerated member having a refrigerated surface having leading and following end portions and convexly curved along its length, an endless flexible belt encompassing said refrigerated surface, means for causing said belt to travel about said refrigerated member and slide along said refrigerated surface, resilient movable means for maintaining said belt under tension in contacting heat transferring relationship with respect to said refrigerated surface, means for maintaining the successive portions of the belt approaching and reaching the leading edge portion of said refrigerated surface in the plane tangent to said edge portion, means for supplying to said belt material to be congealed thereon, and means for progressively deflecting said belt as it leaves said refrigerated surface to remove therefrom the material congealed thereon.

2. In congealing apparatus of the class described, in combination, a stationary refrigerated member having a refrigerated surface having leading and following edge portions and convexly curved along its length, a flexible metal belt encompassing said refrigerated surface, means for causing said belt to travel about said surface and to slide therealong in contact therewith, means for maintaining the successive portions of said belt approaching said leading edge portion in a plane tangent to said edge portion, means for supplying to said belt material to be congealed thereon, means for deflecting said belt as it leaves said refrigerated surface to remove therefrom the material congealed thereon, and resilient means for maintaining said moving belt under tension whereby the desired heat transfer-ring relationship is maintained between said belt

and said refrigerated surface as the belt slides therepast.

3. In congealing apparatus of the class described, a refrigerated member having a convexly curved refrigerated surface having leading and following edge portions, a flexible belt, means for causing said belt to travel under tension about said refrigerated surface to cause a surface of said belt to contact and slide along said refrigerated surface as the belt slides thereover contacting surface of said belt in advance of its contacting said refrigerated surface to maintain a liquid film between said contacting surface and refrigerated surface as the belt slides thereon whereby the heat transferring relationship between said belt and refrigerated surface is improved, friction is reduced, and atmospheric pressure may be utilized to aid in maintaining the two in the desired heat transferring relationship.

4. In congealing apparatus of the class described, a refrigerated member having a convexly curved refrigerated surface having leading and following edge portions, a flexible belt, means for causing said belt to travel under tension about said refrigerated surface in sliding contact therewith, means for supplying a liquid to the under-surface of said belt to wet the contacting surfaces of said belt and refrigerated surface whereby the heat transferring relationship between said belt and refrigerated surface is improved, friction is reduced, and atmospheric pressure may be utilized to aid in maintaining the two in the desired heat transferring relationship, and means for removing said liquid film from said belt after said belt has passed over said refrigerated member.

5. The method of maintaining the desired heat transferring relationship between a stationary curved refrigerated surface having leading and following edge portions and an endless flexible belt caused to slide over said refrigerated surface which comprises the steps of: maintaining said sliding belt under tension against said refrigerated surface, wetting the contacting surfaces of said belt and said refrigerated surface to improve the heat transferring relationship therebetween, and utilizing atmospheric pressure to maintain a close relationship between said surface and said sliding belt.

6. In refrigerating apparatus, in combination, a stationary evaporator having a curved surface, an endless flexible belt contacting said surface, means to move said belt over said surface, and a liquefied film having a freezing point lower than the operating temperature of the evaporator wetting the contacting surfaces of said belt and said evaporator.

7. In refrigerating apparatus, in combination, a stationary evaporator having a curved surface, an endless flexible belt contacting said surface, means for moving said belt over said surface, resilient means to resiliently hold said belt in contact with said evaporator, and a liquid film having characteristics similar to propylene glycol wetting the contacting surfaces of said belt and said evaporator.

8. In refrigerating apparatus, in combination, an evaporator having a refrigerated curved surface, pulley means positioned at opposite ends of said evaporator, an endless belt running on said pulley means and contacting said curved surface, said refrigerated curved surface being positioned above a plane passing through the upper peripheries of said pulley means, resilient means acting through the pulley means at one end of said

evaporator to resiliently hold said belt in contact with said evaporator, and a liquid film having a freezing point lower than the operating temperature of said evaporator wetting the contacting surfaces of said belt and said evaporator.

5 9. In refrigerating apparatus, in combination, an evaporator having a refrigerated curved surface, pulley means positioned at opposite ends of said evaporator, an endless belt running on said pulley means and contacting said curved surface, said refrigerated curved surface being positioned above a plane passing through the upper peripheries of said pulley means, resilient means acting through the pulley means at one 10 end of said evaporator to resiliently hold said belt in contact with said evaporator, a liquid film having a freezing point lower than the operating temperature of said evaporator wetting the contacting surfaces of said belt and said evaporator, 15 a moisture-proof housing enclosing said apparatus, and a refrigerated member positioned within said housing to refrigerate and dehumidify the space enclosed thereby.

20 10. In refrigerating apparatus, in combination, an evaporator having a refrigerated curved surface, a pair of pulleys positioned at the ends of said evaporator, an endless belt mounted on said pulleys, said refrigerated curved surface of said evaporator being positioned above a plane extending between the upper peripheries of said pulleys, and means mounting one of said pulleys for longitudinal movement with respect to said apparatus, the line of said movement being parallel to a plane tangent to the curved surface of said evaporator at the end thereof adjacent said pulley, the uppermost portion of the periphery of said pulley moving in said tangent plane whenever said pulley moves longitudinally with respect to said apparatus.

25 11. In refrigerating apparatus, in combination, an evaporator having a refrigerated curved surface, a pair of pulleys positioned at the ends of said evaporator, an endless belt mounted on said pulleys, said refrigerated curved surface of said evaporator being positioned above a plane extending between the upper peripheries of said pulleys, means mounting one of said pulleys for longitudinal movement with respect to said apparatus, the line of said movement being parallel to a plane tangent to the curved surface of said evaporator at the end thereof adjacent said pulley, the uppermost portion of the periphery of said pulley moving in said tangent plane whenever said pulley moves longitudinally with respect to said apparatus, and a liquid film wetting the contacting surfaces of said belt and said evaporator, said liquid film having a freezing point lower than the operating temperature of said evaporator.

30 12. In refrigerating apparatus, in combination, an evaporator having a curved surface, a plurality of pulleys positioned at opposite ends of said evaporator, an endless belt mounted on said pulleys, a carriage mounted on said apparatus for longitudinal movement with respect thereto, said carriage mounting one of said pulleys, and resilient means urging said carriage outwardly from the end of said apparatus, said carriage moving in a plane parallel to a plane tangent to said curved surface at the end thereof adjacent said carriage, said last-mentioned pulley being of the correct radius so that its uppermost periphery moves in said last-mentioned plane.

35 13. In refrigerating apparatus, in combination, an evaporator having a curved surface, pulley

means positioned adjacent said evaporator, an endless belt contacting said curved surface and running around said pulley means, means for moving said pulley means and said belt, and means maintaining a supply of liquid to the surface of said belt which contacts said evaporator as said belt approaches said evaporator surface and for conserving any excess liquid from the under surface of said belt after said belt has been in contact with said evaporator surface.

14. In refrigerating apparatus, in combination, an evaporator having a curved surface, pulley means positioned adjacent the ends of said evaporator, an endless flexible belt running on said pulley means and contacting said curved surface, means for driving said belt, a supply tank for holding a liquid having a freezing point lower than the operating temperature of said evaporator, means for supplying liquid from said tank to the undersurface of said belt as it approaches said evaporator, wiper means for removing said liquid from the undersurface of said belt after said belt has passed over said evaporator, means for collecting the liquid so removed from said belt, and means for returning said liquid to said tank whereby a liquid film is maintained between the surface of said belt contacting the curved surface of said evaporator.

15. In refrigerating apparatus, in combination, a stationary evaporator having a refrigerated surface, an endless flexible belt contacting said surface, means for moving said belt over said surface, resilient means to resiliently hold said belt in contact with said evaporator, and a liquid film having characteristics similar to propylene glycol wetting the contacting surfaces of said belt and the surface of the said evaporator which said belt contacts.

16. In refrigerating apparatus, in combination, an evaporator having a stationary refrigerated surface convexly curved along its length, pulley means positioned at each end of said evaporator, said refrigerated surface of said evaporator being positioned above a plane extending between the upper peripheries of the pulley means positioned at the ends of said evaporator, and means mounting the pulley means at one end of said evaporator for longitudinal movement with respect to said apparatus, the line of movement of said last-mentioned means being parallel to a plane tangent to the curved surface of said evaporator at the end thereof adjacent said last-mentioned pulley means, the uppermost portion of the periphery of said last-mentioned pulley means moving in said tangent plane whenever said last-mentioned pulley means moves longitudinally with respect to said apparatus.

17. In refrigerating apparatus, in combination, an evaporator having a curved surface, pulley means positioned at opposite ends of said evaporator, an endless metal belt mounted on said pulley means, a carriage mounted on said apparatus for longitudinal movement with respect thereto, said carriage supporting the pulley means at one end of said evaporator, resilient means urging said carriage outwardly from the end of said apparatus, said carriage moving in a plane parallel to a plane tangent to said curved surface at the end thereof adjacent said carriage, said longitudinally movable pulley means being of such radius that its uppermost periphery moves in said last-mentioned plane, and a liquid film having a freezing point lower than the operating temperature of said evaporator wetting the contacting surfaces of said belt and said evaporator.

18. In refrigerating apparatus, in combination, an evaporator having a curved surface, pulley means positioned at opposite ends of said evaporator, an endless belt mounted on said pulley means, a carriage mounted on said apparatus for longitudinal movement with respect thereto, said carriage supporting the pulley means at one end of said evaporator, resilient means urging said carriage outwardly from the end of said apparatus, whereby tension is applied to said belt, said carriage moving in a plane parallel to a plane tangent to said curved surface at the end thereof adjacent said carriage, said longitudinally movable pulley means being of such radius that its uppermost periphery moves in said last-mentioned plane, a liquid film having a freezing point lower than the operating temperature of said evaporator wetting the contacting surfaces of said belt and said evaporator, a moisture-proof housing enclosing said apparatus, and a refrigerated member positioned within said housing for refrigerating and dehumidifying the space enclosed thereby.

19. In congealing apparatus of the class described, in combination, a stationary refrigerated member having a refrigerated surface having leading and following end portions and convexly curved along its length, said refrigerated surface being defined by a plurality of evaporator tube portions each of substantially flat-sided cross section, an endless flexible belt encompassing said refrigerated surface, means for causing said belt to travel about said refrigerated member in sliding contact with said refrigerated surface, resilient movable means for maintaining said belt under tension in contacting heat transferring relationship with respect to said refrigerated surface, means for maintaining the successive portions of the belt approaching and reaching the leading end portion of said refrigerated surface in the plane tangent to said edge portion, means for supplying to said belt material to be congealed thereon, and means for progressively deflecting said belt as it leaves said refrigerated surface to remove therefrom the material congealed thereon.

20. In congealing apparatus of the class described, in combination, a stationary refrigerated member having a refrigerated surface having leading and following end portions and convexly curved along its length, said refrigerated surface being defined by a plurality of evaporator tube portions each of substantially flat-sided cross section, a flexible metal belt encompassing said refrigerated surface, means for causing said belt to travel about said surface in sliding contact therewith, means for maintaining the successive portions of said belt approaching said leading end portion in a plane tangent to said end portion, means for supplying to said belt material to be congealed thereon, means for deflecting said belt as it leaves said refrigerated surface to remove therefrom the material congealed thereon, and resilient means for maintaining said moving belt under tension whereby the desired heat transferring relationship is maintained between said belt and said refrigerated surface as the belt slides therepast.

21. In refrigerating apparatus, in combination, a refrigerating surface defined by a refrigerating member forming a wall portion of a refrigerating system, an endless flexible belt contacting said surface, means for moving said belt over said surface, means to resiliently hold said belt in contact with said refrigerating surface, and a liquid film having a freezing point lower than the oper-

11

ating temperature of said refrigerated surface wetting the contacting surfaces of said refrigerating surface and said belt.

22. In refrigerating apparatus, in combination, a refrigerating surface defined by a rigid refrigerating member forming a wall portion of a refrigerating system, an impervious thin sheet-like member, means for moving said sheet-like member into and out of contacting relationship with respect to said refrigerating surface, a heat conducting fluid film between said refrigerating surface and said sheet-like member, said film having a freezing point lower than the operating temperature of said refrigerating surface, said film improving the heat transfer relationship between said members, and means for supplying material to be congealed to said sheet-like member while in contact with said refrigerated surface.

23. In refrigerating apparatus, in combination, a refrigerating surface defined by a refrigerating member forming a wall portion of a refrigerating system, an impervious endless flexible belt, means for moving said belt over said refrigerating surface in heat transferring relationship thereto, a liquid heat conducting film filling any space between said belt and said refrigerating surface, said heat conducting film having a freezing point lower than the operating temperature of said refrigerating surface, said film improving the heat transfer relationship between said members, and means for supplying material to be congealed to said sheet-like member while in contact with said refrigerating surface.

24. In congealing apparatus, in combination, a refrigerating surface defined by a refrigerating member forming a wall portion of a refrigerating system, an impervious thin flexible member having contacting and freezing surfaces, means for causing relative sliding movement between said members, whereby the freezing surface of said flexible member is progressively cooled, a liquid having a freezing point below the operating temperature of said refrigerating member and capable of spreading between said contacting surfaces, means for supplying said liquid to the contacting surfaces to fill any space therebetween to increase the coefficient of heat transfer between said contacting surfaces, and means for supplying to said freezing surface material to be congealed.

25. In congealing apparatus, in combination, a refrigerating surface defined by a refrigerating member forming a wall portion of a refrigerating system, an impervious thin flexible member having a contacting surface and a freezing surface, means for causing relative sliding movement between said members, whereby the freezing surface of said flexible member is successively cooled, a liquid having a freezing point below the operating temperature of said refrigerating member and capable of spreading between said contacting surfaces, means for supplying said liquid to the contacting surfaces to fill any space therebetween to increase the coefficient of heat transfer between said contacting surfaces, said liquid also having the properties of a lubricant to aid the sliding movement of said flexible member with respect to said refrigerating surface, and means for supplying to said freezing surface material to be congealed.

26. An ice making apparatus comprising an evaporator forming part of a closed refrigerating system and having a refrigerating surface of constant curvature; an endless flexible belt of heat conducting material; means maintaining a portion of said belt in close proximity to a major

12

portion of said refrigerating surface and causing said portion of the belt to conform in curvature to said surface, said means including an element spaced from said refrigerating surface and presenting a curved surface in contact with the inner surface of the belt; and means for applying water to be frozen to the exterior of the belt; said belt being movable relative to said surfaces and said apparatus being constructed and arranged to hold a quantity of liquid having a freezing point below the lowest temperature to be reached by the operation of said apparatus and to cause the relative movement of the belt with respect to the refrigerating surface to interpose a portion of said liquid in the form of a film between the latter and the portion of the belt conforming thereto in curvature and to flex the belt across the second mentioned curved surface to break a layer of ice frozen thereto.

27. In refrigerating apparatus, in combination, an evaporator construction including a continuous curved refrigerated surface, an endless flexible belt encompassing said refrigerated surface and contacting a portion thereof, deflector means adapted to flex successive sections of said belt out of contact with said evaporator, and an antifreeze positioned between said belt and said refrigerated surface adapted to engage and spread over the contacting surfaces thereof; said deflector means having belt-supporting surfaces predetermining said endless path in the regions of maximum belt flexure, said belt-supporting surfaces extending across and supporting the marginal edges of the inside of said belt.

28. In refrigerating apparatus, in combination, an evaporator construction including a continuous curved refrigerated surface, an endless flexible belt encompassing said refrigerated surface and contacting a portion thereof, deflector means adapted to flex successive sections of said belt out of contact with said evaporator, and an antifreeze positioned between said belt and said refrigerated surface adapted to engage and spread over the contacting surfaces thereof; said deflector means having belt-supporting surfaces predetermining said endless path in the regions of maximum belt flexure, said belt-supporting surfaces extending across and supporting the marginal edges of the inside of said belt, a pair of endless rubber-like members secured in face-to-face contact with the under side of said belt one along each marginal edge thereof, said members being interposed between said belt marginal edges and said deflector means.

CROSBY FIELD.
